UNITED STATES PATENT OFFICE.

FRANK X. LEUTHNER, OF BUFFALO, NEW YORK, AND FRANK TICKNER, OF SHARPSVILLE, PENNSYLVANIA; FRANK J. LEUTHNER EXECUTOR AND MINNIE LEUTHNER TAYLOR EXECUTRIX OF SAID FRANK X. LEUTHNER, DECEASED.

MOLDING APPARATUS.

1,018,669.

Specification of Letters Patent. Patented Feb. 27, 1912.

Application filed March 2, 1910, Serial No. 546,821. Renewed January 11, 1912. Serial No. 670,725.

To all whom it may concern:

Be it known that we, FRANK X. LEUTHNER and FRANK TICKNER, citizens of the United States, residing at Buffalo, in the 5 county of Erie and State of New York, and Sharpsville, in the county of Mercer and State of Pennsylvania, respectively, have invented new and useful Improvements in Molding Apparatus, of which the following 10 is a specification.

This invention relates to a molding apparatus for making tubular castings, such as ingot molds, and more particularly to an apparatus of this character which comprises a 15 collapsible core-barrel such as shown in Letters Patent of the United States No. 868,607, dated October 15, 1907.

In the apparatus shown and described in the above mentioned patent it is necessary 20 to employ a plurality of extracting or ejecting devices for removing the core-barrels of different sizes of molds from the castings and flask, which ejecting devices are provided with heads, centers or posts to suit 25 the different sizes of collapsible cores with which the same engages for ejecting the core-barrel from the flask and casting and limit the upward movement of the side plates on the core body during this operation.

One of the objects of this invention is to so construct the collapsible core-barrel that the upward movement of the plates on the core-body or column is limited by means 35 arranged directly on these parts, thereby permitting of using the same extracting device on all of the molds regardless of their size and effecting a corresponding reduction in the cost of the equipment.

40 In the collapsible core-barrel of the patent referred to the side plates were surrounded by bands which confined these plates on the core-body while the facing of sand was applied to the outer side of the 45 same and the metal was poured into the mold containing this core. Owing to the looseness of these bands it has been necessary for one or more men to stand by during the operation of removing the core from 50 the flask and casting in order to prevent the side plates from falling away from the core body when the bands are shifted which

otherwise would necessitate re-assembling of the core-body and side plates before the same can be again coated with sand for 55 making another core.

Another object of this invention is to provide simple, inexpensive and efficient means whereby the side plates are permanently connected with the core-body or column but 60 which permit the side plates to move lengthwise of the core-body or column the required extent to permit the collapsible core-barrel to be disengaged from the casting, thereby avoiding the necessity of employing 65 any one to prevent dismemberment of the collapsible core-barrel during the stripping operation and also avoiding the loss of time heretofore involved in re-assembling the collapsible core-barrel when the parts became 70 dismembered.

A further object of the invention is to improve the device of our patent by providing holding connections for the core members or plates which are internal of the 75 structure.

In the accompanying drawings consisting of 2 sheets: Figure 1 is a vertical section of our improved collapsible core-barrel associated with the flask of a mold and the 80 means for extracting or ejecting the core-barrel from the casting. Fig. 2 is a top plan view of the core-barrel. Fig. 3 is a bottom plan view thereof. Fig. 4 is a side elevation of the same. Fig. 5 is a detached vertical 85 section of the collapsible core-barrel. Fig. 6 is a horizontal section in line 6—6, Fig. 5.

Similar letters of reference indicate corresponding parts throughout the several views.

90 In its general organization the collapsible core-barrel of this molding apparatus resembles that shown in Letters Patent of the United States No. 868,607, which has been previously referred to and comprises a tubular core-body A which tapers upwardly from the bottom to the top thereof and is preferably made of cast metal and of rectangular form in cross section although not necessarily so. At its bottom said body has 100 an outwardly projecting flange a.

B, B represent the side plates of the core-barrel which are arranged around the body A thereof and normally rest at their lower

edges on its flange *a*. Said plates *B* conform to the general contour of the external surfaces of the body *A* and they are of such width that when placed in position around said body to rest at their lower ends on the flange *a*, the several plates are separated slightly from each other at their opposing upright longitudinal edges. On its inner side each plate *B* is provided with two or 10 more longitudinal upright ribs *b* which engage similar ribs *b'*, *b''* formed on the flat surfaces of the body near the corners thereof. The several side plates are provided with openings *c* in which the outer coating 15 *C* of the molding sand of the core can anchor itself and which also form vent passages through which the moist air can escape in drying the molding sand as well as the gases which are generated during the 20 operation of casting.

The several side plates are coupled with the body by means which permit the same to move laterally toward and from the side of the body as well as lengthwise thereof when 25 erecting the core or when ejecting the same from the casting but which prevent the side plates from becoming disconnected from each other or from the core-body. The preferred means for this purpose which are 30 shown in the drawings comprise a plurality of holding connections shown as consisting of horizontal coupling bolts or tie rods *D* each of which passes transversely through a pair of corresponding longitudinal slots 35 *e*, *e* formed in opposite sides of the core-body and through aligned openings *f* formed in the side plates which are arranged on opposite sides of the core-body. One end of the bolt is preferably provided with a head 40 *d* which bears against the outer side of one side plate and the other end of this bolt is provided with a cotter pin or key *g* which engages with the outer side of the other side plate. At the outer ends of the openings *f* 45 the side plates are provided with recesses *h* which receive the head and pin of the respective coupling bolt so that the opposite ends of the bolt are flush with the outer surfaces of the side plates and are not liable to 50 interfere with obstructions when handling the same as would be the case if the coupling bolts projected at their opposite ends beyond the outer surfaces of the side plates.

Although the number of bolts which are 55 employed for tying together the core-body and each pair of side plates on opposite sides of the same may be varied, it has been found that two of such bolts, as shown in the drawings, are suitable for this purpose. In 60 order to permit the coupling bolts or tie rods of one pair of plates to clear those of the other pair of plates, these coupling bolts are arranged vertically out of line with each other, as shown in Figs. 1 and 5.

Although the upward movement of the 65 side plates on the core-body may be limited by engagement of the coupling bolts with the upper ends of the slots, it is preferable to employ for this purpose a stop device for each side plate which is independent of such 70 coupling bolts and which arrests the upward movement of each side plate relatively to the body independently of the other side plates. The preferred means for this purpose comprise an integral stop lug *i* projecting 75 inwardly from the upper part of each side plate and provided with an upwardly-facing stop surface or shoulder and a plurality of integral stop lugs *j* projecting outwardly from the upper part of the body 80 above the stop lugs of the side plates and each provided on its underside with a downwardly facing stop surface or shoulder which is adapted to be engaged by the stop 85 face on the adjacent side plate.

In the completed condition of the core-barrel,—the side plates are spread and lowered, so that their lower ends rest upon the flange *a*, as shown in Figs. 4 and 5, and the outer sides of the side plates and the margin 90 of the flange *a* are coated with a layer of molding sand *C*. When thus prepared the core is placed upon a bottom plate or drag *K* and surrounding it is placed the flask *L* which rests on the drag and has an inner 95 layer or lining *l* of sand which is separated from the sand surface of the core by an intervening annular space or mold cavity *M*, as shown in Fig. 1.

After the molten metal is poured into the 100 mold cavity the flask is raised together with the casting and the core is ejected downwardly therefrom by an extracting or ejecting device which is preferably constructed substantially like that shown in the Letters 105 Patent heretofore referred to. Said extractor comprises a head, center or post *N* which is adapted to bear against the upper end of the neck *n* at the top of the core body, two horizontally disposed levers *o*, *o* pivoted at 110 their upper inner ends to opposite sides of the head, two upper chains *p*, *p* connected at their lower ends with the outer ends of said levers while their upper ends are connected with a ring *P* which is adapted to be 115 connected with a crane or other suitable lifting device, and two lower chains *q*, *q* connected at their upper ends with said levers between their inner and outer ends and provided at their lower ends with hooks *Q*, *Q* 120 which are adapted to engage with an outwardly extending horizontal flange *R* at the upper edge of the flask.

Upon applying a lifting force to the ring *P* the levers *o*, *o* are caused to be turned in 125 such a direction that the head *N* is pressed downwardly against the neck of the core-body while the hooks are pulled upwardly,

thereby causing the core-body to be pushed downwardly and the flask to be raised together with the casting therein and the side plates of the core-barrel. During this upward movement of the side plates the same slide upwardly with their beveled or inclined ribs along the correspondingly shaped surfaces of the tapering body. Inasmuch as the side plates in their normal position do not engage each other at their upright longitudinal edges they are permitted, when raised, to move inwardly so that they and the sand covering of the core-barrel are no longer internally supported and may collapse and thereby become separated from the inner surface of the casting. When the side plates have been raised so that their stop lugs *i* engage with the undersides of the stop lugs *j* on the outer side of the core-body,—the continued upward movement of the flask causes said plates and the sand covering thereof to be disengaged from said casting. While the plates are thus raised relatively to the core-body the coupling bolts *D* slide vertically in the slots *e* of the core-body and as the plates contract or move toward each other on the upper part of the core body, as shown by dotted lines in Fig. 5, the same slide horizontally upon the coupling bolts.

As the core-body and side plates are ejected from the flask and casting the core-body and side plates are held by the coupling bolts *D* in their assembled condition without necessitating any hands for this purpose, thereby reducing the cost of labor and facilitating the preparation of a core for the next mold.

The advantages of our invention will be apparent to those skilled in the art.

The objection to the loose bands of our prior patent is entirely overcome, and the holding connections for the core members or plates are internal. The plates form a permanent part of the core and are not loose so that they fall off as in our prior device. The upward stripping of the mold and casting causes the relative endwise movement of the core members or plates and the column or core body, which gives the contraction for collapse, thus allowing quick and easy stripping.

The holding connections for the core members or plates may be varied widely. For instance, these connections may extend to the column instead of to each other. The column may be of different lengths, and may be varied widely in shape, length and size. The core members may be arranged to expand and contract without longitudinal movement, except that between the core members and the column. The longitudinal openings between the core members may be at four corners or at two opposite cor-

ners, or may be intermediate of the corners, 65 the core may be formed of two plates or core members, or more, and many other changes may be made in the form and arrangement of the parts without departing from our invention. 70

We claim as our invention:

1. A collapsible core having longitudinal core members shaped to form an angular structure, said members have adjacent edges separated by longitudinally open spaces, 75 and connections for said core members, extending within the structure and holding the members expanded, said connections being arranged to allow collapse of the members on lifting the flask and contained casting, substantially as described. 80

2. In a collapsible core, a column having a tapering portion, core members surrounding the column and forming a structure of angular cross section, said core members 85 having some of their adjacent edges separated by longitudinally open spaces arranged to receive coating material, and holding connections for the core members extending within the structure and arranged 90 to hold the members expanded, said connections being arranged to allow collapse of the members on endwise movement of the flask and casting relative to the core, substantially as described. 95

3. A collapsible core having core members shaped to form an upwardly tapering structure of angular cross-section, said members having adjacent edges separated by longitudinally open spaces arranged to receive the coating material, holding connections for said members to permit expansion and contraction thereof, said holding members being internal of the structure, and a column having a tapered portion arranged 100 for movement relative to the members, said column operating by sliding contact to expand or contract the core members; substantially as described. 105

4. A collapsible core having core members with at least some of their adjacent edges separated by longitudinally open spaces to receive coating material, a central column having a tapering portion arranged to bear directly upon portions of the core members 110 to hold them expanded, and holding connections for the core members arranged internally of the structure, said connections being arranged to allow contraction of the core members on lifting of the flask and holding casting therefrom, substantially as described. 115

5. A collapsible core having core members surrounding a central column, said column being arranged to expand and hold the 120 core members expanded and the core having longitudinally open spaces arranged to receive the coating material, and holding

connections for the core members internal of the structure and arranged to allow contraction of said members on lifting of the flask and hollow casting therefrom, substantially as described.

6. A core-barrel comprising a body having longitudinal slots, a plurality of plates surrounding said body and provided with openings in line with the slots of the body, and 10 coupling bolts each extending transversely through the corresponding slots of the body and the openings of the plates on opposite sides thereof and having inwardly facing shoulders outside of said plates.

15 7. A core-barrel comprising a body having longitudinal slots, a plurality of plates surrounding said body and provided with openings in line with said slots and recesses at the outer ends of said openings, and a plurality of coupling bolts each of which extends transversely through the corresponding slots of the body and the openings of the plates on opposite sides of the same and having a head at one end which is arranged in 20 one of said recesses and a cotter pin at its opposite end arranged in the opposite recess.

8. A collapsible core having core members shaped to form an endwise tapering structure of angular cross-section and having adjacent edges separated by longitudinally open spaces to receive coating material, internal connections for said members arranged interior of the structure and allowing expansion and contraction of the members, and a central column having a tapering portion arranged to provide expansion and contraction by relative endwise movement of the column and members, said column having a head portion arranged to project above the top of the mold; substantially as described.

45 9. A collapsible core having a central column, with a tapering portion and an upwardly projecting head portion, and core members inclosing the column and provided with connections internal of the structure to hold them in place, the column being arranged to expand and hold the core members expanded, and the connections being arranged to allow collapse of the core members on lifting the flask and hollow casting therefrom, substantially as described.

50 10. A collapsible core having surrounding core members shaped to form a structure of angular cross section having open longitudinal core spaces to receive coating material, a central column having a tapered portion and a top head portion to project above the casting, and internal holding connections 55 for the core members engaging the column

and arranged to allow collapse of the core members on lifting of the flask and hollow casting therefrom, substantially as described.

11. A collapsible core having core members shaped to form an endwise tapering structure of angular cross-section, said members having adjacent edges separated by longitudinally open spaces arranged to receive coating material, a central column arranged for relative longitudinal movement between it and the core members, and stops arranged to limit this relative endwise movement; substantially as described.

65 12. A collapsible core having inclosing core members forming a structure of angular cross section with open longitudinal corner spaces to receive coating material, a central column having a tapered portion and an upwardly projecting head to receive the ejector, and internal mechanism arranged to 70 couple the column and core members together and allow for expansion of the column while permitting collapse of the core members on lifting of the flask and hollow casting therefrom, substantially as described.

75 13. A collapsible core having a central column with a tapering portion and a head portion arranged to be engaged by an extractor, and core members inclosing the column and provided with connections internal 80 of the structure to hold them in place, the column being arranged to expand and hold the core members expanded, and the connections being arranged to allow automatic collapse of the core members when the flask is 85 lifted by an extractor bearing on the column, substantially as described.

90 14. A collapsible core having core members surrounding a central column, said column being arranged to expand and hold the core members expanded, the core having longitudinally open spaces to receive the coating material, and holding connections for the core members internal of the structure and arranged to allow automatic contraction of said members on lifting of the flask by an extractor engaging the column, 95 substantially as described.
